UNITED STATES PATENT OFFICE.

ROMAN E. V. ANGRESIUS, OF NEWARK, NEW JERSEY.

SUPPOSITORY.

1,096,884.

Specification of Letters Patent.

Patented May 19, 1914.

Application filed January 25, 1913. Serial No. 744,065.

To all whom it may concern:

Be it known that I, ROMAN E. V. ANGRESIUS, a citizen of the United States, residing at Newark, in the county of Essex and State of New Jersey, have invented certain Improvements in Suppositories, of which the following is a specification.

The objects of this invention are to produce a suppository with an inclosing cover or shell; to form the body portion of the suppository by means of said cover or shell, without the necessity of touching the ingredients with the fingers; to thus enable each suppository to be made up under perfect sanitary conditions; to avoid the use of any machinery or appliances other than said cover or shell in making up the suppository; to thus enable the suppositories to be made very cheaply; to save time in filling prescriptions for suppositories and to enable them to be made all of the same shape and size; to provide means for readily and conveniently removing the shell or cover when it is desired to administer the suppository to a patient; to insure that the suppository be kept clean and fresh until used, and to obtain other advantages and results as may be brought out in the following description.

Referring to the accompanying drawings, in which like numerals of reference indicate the same parts throughout the several views, Figure 1 is an elevation of the cover or shell of my improved suppository without its cap or top; Fig. 2 is a similar elevation of the cap; Fig. 3 is a sectional view on line A—A of Fig. 1 looking in the direction indicated by the arrow; Fig. 4 is a view in perspective showing the method of filling the shell without touching the substance or material containing the medicinal preparation; Fig. 5 is an elevation of the suppository complete, as made up by the druggist; Fig. 6 is a perspective view illustrating the removal of the shell or cover preparatory to administering the suppository, and Fig. 7 is a perspective view of the body portion of the suppository and the shell or cover as removed therefrom.

In the specific embodiment of the invention illustrated in said drawings, the reference numeral 1 indicates a shell of any material suitable for the purpose, such as gelatin, and of the common and well-known conical shape of a suppository, with its base or large end open. Extending along the

inner surface of the wall of said shell shall 1, and preferably embedded or partially embedded therein, is a rip-string 2, and preferably this string extends from a point at the open end 60 edge of the shell longitudinally to the apex and then back again to the open end edge along the opposite side of the interior chamber or cavity of the shell, as shown in Fig. 3. Both of the ends 3, 4 of the rip-string may 65 hang out over the edge of the shell, as shown in the drawings, or if preferred one of them may be cut off close to the edge.

It will be seen from the further description of the invention herein that the exact 70 arrangement and disposition of the rip-string upon the inner wall of the shell could be varied considerably, so long as it was adapted to accomplish the purposes set forth.

In making suppositories according to my invention, the druggist places the coca butter or other equivalent material containing the medicinal preparation upon a suitable surface, as shown at 5 in Fig. 4, and then 80 takes the shell 1 in his fingers holding it inverted and with the ends 3, 4 of the rip-string caught back out of the way. By pressing the shell down into the material before him, repeatedly, the shell is filled, and 85 its contents are more or less compact and solid according to the length of time he continues this process and the pressure he uses. It will be understood that so much of the substance as goes into the shell at each down- 90 pressing of the same sticks there, especially at the right temperature, and that the entrance of each additional portion forces previous portions up the shell toward its apex. In this way, by continuing the process long 95 enough and using sufficient pressure, a compact body portion 6 can be easily and very quickly formed inside the shell.

It is to be noted that the hands of the druggist in filling the shell have no occasion to touch the mixture, so that possibility of contamination is avoided. Furthermore, it is to be understood that in filling a certain prescription only a sufficient amount of mixture is compounded to fill the prescribed 105 number of shells and thus any waste in preparing the suppositories is avoided. The filling can also be done quickly and neatly. When a shell has been thus filled, a cap 7 is slipped over its open end, so as to entirely 110 inclose the body portion 6 of the suppository from exposure or contact with any object

whereby infection might be inadvertently carried to the user. This top or cap 7 I have shown as cylindrical in shape, frictionally fitting around the shell adjacent its 5 open end, although it is deemed within the scope of the appended claims to form this cap in any shape desired. It will be understood that the ends 3, 4 of the rip-string do not interfere with putting on this cap 7, 10 preferably extending between it and the shell and projecting alongside the shell toward its apex, as shown in Fig. 5. In this condition, my improved suppository can be kept for a considerable time without any 15 drying up or deteriorating, and can also be conveniently and safely handled.

When the suppository is to be used, the cap 7 is first removed and thrown away, and then the rest of the suppository is immersed 20 in water for a minute or two so as to soften the shell 1. When taken out of the water, with the shell properly softened, the rip-string 2 will tear its way through the shell, upon being pulled or drawn, so as to divide 25 the shell into two parts or halves 8, 8 which can be readily detached from the body portion 6, as shown in Fig. 7. I have illustrated in Fig. 6 a convenient way of holding the suppository in one hand and pulling the rip-string 2, first by one end 3 and then by the other end 4, or if preferred the pulling may all be done upon one and the same end of the rip-string, but obviously said rip-string may be utilized in any manner desired to properly tear the shell 1 so that it 30 can be separated from the body portion 6.

The purpose of my invention is to remove the shell 1 from the body portion 6 with a minimum amount of difficulty and handling,

so that said body portion can be administered to the patient and the shell and rip-string thrown away, and I desire it to be understood as within the scope of the invention that any suitable means for accomplishing this can be employed, those shown 45 in the drawing being merely illustrative.

Having thus described the invention, what I claim is—

1. A suppository comprising a shell, a body portion in said shell, a removable closure for said shell, and means for ripping said shell to disengage it from said body portion. 50

2. A suppository comprising a shell, a body portion in said shell, a closure for 55 said shell, and a rip string for said shell adapted to rip the same apart when said closure is removed.

3. A suppository comprising a shell, a body portion in said shell, and a rip-string 60 upon the inner surface of said shell projecting outside the same.

4. A suppository comprising a shell, a body portion in said shell, and a rip-string 65 partially embedded in the inner wall of said shell having one end projecting outside said shell.

5. A suppository comprising a shell, a body portion in said shell, a rip-string upon 70 the inner surface of said shell projecting outside the same, and a cap closing said shell, and confining the ends of said rip-string.

ROMAN E. V. ANGRESIUS.
